DELIVERY FOR TOBACCO STRIPPERS

Rupert E. Rundell, Rockville Centre, N. Y., assignor to International Cigar Machinery Company, a corporation of New Jersey

Application January 25, 1936, Serial No. 60,808

13 Claims. (Cl. 131—125)

This invention relates to improvements in tobacco stemming machines, more particularly to the delivery mechanism thereof, and is in the nature of an improvement upon the machine disclosed in Letters Patent 2,019,721 to Nejedly, granted November 5, 1935. Its main object is to provide improved means for detecting and segregating unstemmed or insufficiently stemmed leaves. Stemmed leaves, especially when used as cigar fillers, should be devoid of any thick stem portions which may be left therein by the improper operation of the stemming mechanism. For example, a leaf may occasionally pass through the stemming machine without being properly caught by the stemming mechanism, therefore it is delivered with more or less of the thick portion of the stem still present. In this case the imperfectly stemmed leaf should be segregated. To this end there is provided mechanism controlled by the unstemmed or insufficiently stemmed leaves for diverting the latter positively from the good leaves. A suitable form of mechanism is illustrated herein, comprising a detector of known construction actuated by the passage of defective leaves thereunder to move a traveling endless belt into position to receive the defective leaf or leaves which would otherwise be deposited on an endless conveyor belt for delivery at the desired point. Thus, the present invention provides for segregating the unstemmed leaves and the imperfectly stemmed leaves positively from the path in which they are normally advanced to the desired point of delivery.

In this respect the present invention is in the nature of an improvement upon the known practice as disclosed in Letters Patent to Nejedly, No. 2,019,721, where a machine of the general type shown in the patent issued on November 20, 1934, No. 1,981,470, to the present applicant, provides for carrying an unstemmed leaf in the normal path, but beyond the point where the properly stemmed leaves are deposited, the segregation being effected at the time the properly stemmed leaves are discharged from the normal path.

The thin portion of the stem near the tip of the leaf, which is left in the leaf, is sometimes objectionable because, when used as cigar filler it may press into or otherwise injure the cigar wrapper. Moreover, when crushed, a greater portion of the stem may be left in the properly stemmed leaves, since the stem portion remaining there will likewise be crushed to proper size; and a greater weight or yield of stemmed leaves

will be obtained. Furthermore, in case the stemmed leaves are to be blended, it is desirable that they be split at the tip so that the two halves of the leaf can be blended separately. A second object of the invention therefore is to crush the portion of the stem remaining in the leaves after stemming, and then split the same, whereby a greater weight of cigar filler suitable for blending will be obtained.

A further object of the invention is to compress the "strip," to the end that any wrinkling or curling thereof may be removed.

Still another object is to prevent sticking of the "strip" to the conveyor belts after the suction has been cut off in the suction chamber under which the belts travel.

The mechanism provided in the present invention for achieving the first object enumerated may consist of a roller suspended from one arm of a bell-crank lever so as to ride on the leaf delivered by the stemming machine, the other arm carrying an electric contact-maker. When a properly stemmed leaf passes under this roller, it does not raise it sufficiently to close the contact, but an unstemmed or insufficiently stemmed leaf with a thick portion of its stem still present will do so and thereby energize a solenoid controlling suitable mechanism for moving an endless belt into the path of the faulty leaf, thus diverting the same from its normal delivery path and carrying it to a trough provided for this purpose, so that it may be returned to the stemming machine or otherwise disposed of. By diverting the faulty leaves positively instead of carrying them beyond the point at which the good leaves are deposited, as heretofore, there is no possibility of mixing the two types of leaves.

To achieve the second object, a pair of superimposed compressor rolls are provided, the upper of which is suspended from a pivoted horizontal arm made to oscillate in the vertical direction, the swinging movement of this arm being so timed that the upper roll engages the advancing leaf only during the passage of the unstemmed portion at its tip, thereby crushing the same.

For splitting the stemmed leaves, cutter mechanism is incorporated in the delivery mechanism, so timed as to descend upon the leaf during the passage of a given length of its tip. The cutter is mounted on an oscillating arm and in its cutting position engages with a stationary anvil roller. At each side of the cutter an endless horizontal belt guides the leaf and prevents it from leaving the conveyor belt and sticking to the cutter.

The third object is achieved by providing a large drum and a series of additional endless belts, coacting with a series of conveyor belts for the good leaves, the halves of the split leaf passing around the drum between the respective conveyor and additional belts. The pressure exerted by the moving belts upon the leaf during this comparatively long travel effectively straightens out the leaf so that it is delivered in flat condition.

To accomplish the fourth object there may be provided members disposed in recesses in the bottom of the suction chamber and actuated by the air-expelling plate of the latter and movable between the conveyor belts to engage the adhering leaves and strip them from the belts.

With these and other objects not specifically mentioned in view, the invention consists in certain constructions and combinations herein-after fully described and then specifically set forth in the claims hereunto appended.

In the accompanying drawings, which form a part of this specification and in which like characters of reference indicate the same or like parts:

Fig. 1 is a sectional side elevation of the delivery end of a stemming machine equipped with the various features of the present invention;

Fig. 2 is an enlarged end elevation on line 2—2 of Fig. 1, showing the stem slitter in operating position;

Fig. 3 is an enlarged sectional end elevation on line 3—3 of Fig. 1, showing the construction of the delivery belt suction chamber and the combined pneumatic ejecting and leaf-depositing device;

Fig. 4 is a sectional side elevation of a suitable form of stemming mechanism with which the present invention may be combined; and

Fig. 5 is a front elevation of the same.

Generally stated, in the particular embodiment of the invention herein illustrated, the tobacco leaves are stemmed and the remaining portion of their stems are crushed and then split to separate the two halves of the leaves.

Apparatus illustrative of one way in which the invention may be carried into effect may, as shown herein, comprise mechanism for stemming tobacco leaves, mechanism for advancing the stemmed leaves, a device for detecting unstemmed and insufficiently stemmed leaves among the leaves advanced by said leaf-advancing mechanism, and means controlled by said device for diverting the unstemmed and insufficiently stemmed leaves from said leaf-advancing mechanism. In the best constructions contemplated there are provided members for crushing the remaining stem portions of the advancing leaves and means for splitting the same to separate the halves of the leaves.

This process and apparatus may be widely varied in construction, for the specific method and structure selected to illustrate the invention are but certain of many possible concrete embodiments of the same. The invention therefore is not to be restricted to the particular embodiments chosen as illustrative of the invention.

Referring first to Figs. 4 and 5, wherein a stemming mechanism similar to that shown in Patent No. 1,864,765, granted June 28, 1932, is illustrated, a tobacco leaf T may be manually or automatically inserted tip first between the flaring lips 210 of the two halves of a suction chamber 211 having pipes 212 connected to a suitable source of suction (not shown), whereupon the leaf is

nipped between belts 213 driven by rolls 214 and looped over guide rollers 215, and carried through the mouths of the two halves of the suction chamber. In its passage therethrough the leaf is spread out by the suction which acts in the direction of the arrows (Fig. 1). The outspread leaf is guided from the belts 213 by sets of belts 213a driven by rolls 214 and trained over rollers 216, the leaf being delivered from between the latter on to the periphery of a perforated sleeve 217 rotating on an apertured cylindrical suction box 218 connected by branch pipe 219 to one of the pipes 212 leading to the source of suction. When the tip of the leaf reaches the sleeve 217 it is retained thereon by the suction applied through the aperture of the suction box and the perforations of the sleeve, and the leaf is carried to a point where it is gripped between the drum and a loop 220a of a conveyor belt 5 (Fig. 4). This belt runs over suitable guide rollers 221, 222, 223 and 225. Parallel with and in opposed relation to the sleeve 217 is a rotating cylinder 226 having a series of slotted circumferential flanges 227. A series of plungers (not shown) are mounted for movement axially of the cylinder and each provided with a row of inclined pins 229 movable in slots of the flanges. These pins coact with the slotted flanges to grip the portion of the stem projecting above the laminae of the leaf from the sleeve 217, as described in the above mentioned patent. The gap between the sleeve 217 and the cylinder 226 is set to accommodate the thickness of the leaf portion and so much of the tip end of the stem as it is desired to leave in the leaf. Thus that portion of the stem thicker than the distance between the sleeve and the cylinder will project into the spaces between the flanges and the inclined pins and be gripped. Since the surface of the sleeve 217 and the grippers 229 and flanges 227 of the drum 226 travel in diverging paths, the stem will be torn away from the laminae, as shown in Fig. 4. Suitable brushes 230 and 231 serve to strip any diverging leaf or stem portions from the members 217 and 226, and the stripped stems pass into the chute 232. The stemmed leaves are thus delivered in outspread condition to the portion of the machine shown in Fig. 1, wherein the portion of the stems remaining in the leaves is crushed and slit to divide the leaves into halves, and unstemmed or improperly stemmed leaves are segregated.

Referring now to Fig. 1, the leaf L discharged from the stemming mechanism of the machine is carried by the endless belt 5 to the feeler or detector roller 6. The belt 5 is driven from a drum 7 on a shaft 8 by a chain 9 trained over sprockets on the shaft 8 and the cam shaft 10 of the machine, and runs over guide rollers 11 and 12. The roller 6 is suspended from a bell-crank 13 carrying an adjustable electric contact-maker 14 opposite a contact 14a, which may be a grounded leaf spring and is pressed down against the passing leaf by a weak tension spring 15. The contact-maker 14 is normally out of engagement with the leaf spring 14a and is so adjusted that it engages the leaf spring 14a and thus closes an electric circuit when the roller 6 is raised above a given height by the passing leaf. Thus, a leaf with the thick part of its stem entirely removed will pass under the roller 6 without affecting the electric contact, but an unstemmed leaf or one not properly stemmed will close the circuit and thereby will energize a solenoid and effect the movement of its core in a direction which will set into operation mechanism, hereinafter described,

which will later deflect the faulty leaf from its normal path and separate it from the good leaves.

Upon emerging from under the feeler roller, the leaf L passes over a drum 16 rotating on a shaft 17. With the drum 16 intermittently engages an oppositely revolving drum 18 on a shaft 19 mounted in the free end of an arm 20, the arm 20 being oscillated on a shaft 21 by a rod 22 actuated by a cam lever 125 engaging a cam 126 on shaft 10. The oscillations of arm 20 are so timed that the engagement of the drums 16 and 18 takes place upon the arrival of leaf L, but lasts only during the passage of the tip of the leaf, so as to crush the thin portion of the stem left in the same by the stemming mechanism of the machine. Scrapers 23 and wiping pads 24 are arranged to bear against each of the drums 16 and 18 and keep its surface clean during the operation of the machine. The pads 24 are made of felt or other suitable material and moistened with water from a reservoir 25 and are carried by and kept in wiping motion by linkage (not shown) connected to a rocker arm actuated from cam shaft 10.

From the compressor drums the leaf is guided by revolving stripping brushes 26 onto a pair of transfer belts 27 running over sets of rollers 28, 29 and 30 on shafts 31, 32 and 33, respectively. On shaft 32, between the rollers 29, is mounted an anvil roller 34 with which intermittently engages a cutter 35 rotating on a shaft 36 in an arm 37 pivoted on a shaft 38. The arm 37 is oscillated by a rod 39 connected to a cam lever or the like 127 suitably actuated from the cam shaft 10 by a cam (not shown) in such a manner that the cutter 35 is in its operating position shown in Fig. 2 just long enough to split lengthwise the stem tip previously crushed by roller 18. A set of endless belts 40 arranged on each side of cutter 35 run over sets of rollers 41 and 42 on shafts 43 and 44, these belts being parallel with and in close proximity to the belts 27 so as to hold the leaf down on the latter belts and prevent it from sticking to the cutter.

Shaft 17 of roller 16 is driven by a chain 45 from shaft 8 of drum 7 and in turn drives shaft 31 of rollers 28 by a sprocket chain 46. A gear 47 on shaft 31 meshes with a gear 48 on shaft 38 of arm 37, the shaft 38 driving the shafts 21, 36 and 43 by sprocket chains 49, 50 and 51 respectively, and the shaft 19 being driven from shaft 21 by a sprocket chain 52.

From the end rollers 30 of belts 27 the now separated halves of the leaf are transmitted on to the endless conveyor belts 53 if the guide rollers 54 of the endless conveyor belts 55 are in their normal upper position 54' shown in dotted lines in Fig. 1. But if the rollers 54, which turn on a shaft 56, are in their lower position shown in full lines, the unstemmed or insufficiently stemmed leaf L is diverted on to the belts 55 and thence into a trough 59 provided for its reception.

The shaft 56 of the rollers 55 is carried by arms 60 pivoted on brackets 61 and is connected by a link 62 with one end of a balance arm 63. The other end of arm 63 is connected by a link 64 with a cam lever 65 fulcrumed on a shaft 66 and having a follower 67 held down on a plate cam 68 on shaft 10 by a tension spring 69. To the shaft 10 is fastened a gear 70 which drives a gear 71 on a shaft 72. In the web of the gear 71 are slidably supported a number of equi-distantly spaced pins 73, their number depending on the gear-ratio chosen, and from the hub of

cam lever 65 extends an arm 74 having an arcuate face conforming with the path of the pins 73. In their normal position the rear ends of the pins 73 are flush with the rear face of the web of gear 71 so that the arm 74 can move freely, but when they are made to protrude from the web, as hereinafter described, they engage the curved face of arm 74 and prevent the cam lever 65 from moving, so that the tension of the spring 69 cannot raise the arms 60 when the roller 67 has run off the high point of cam 68, wherefore the rollers 55 remain in their lower position.

On a pedestal 75 carrying shafts 66 and 72 is mounted a solenoid 76, the core 77 of which, by a link 78, is connected with a bell-crank lever 15 79 having an arcuate pusher 80 arranged to engage the pins 73. The solenoid 76 is connected to a source of A. C. electric current lines 81 and 82, the latter being provided with a circuit breaker 83 controlled by an electromagnet 84 connected to one terminal of the secondary of a transformer 85 by lead 86 and connected by lead 87 to contact-maker 14. The primary of the transformer 85 is connected to the lines 81 and 82, and the other terminal of its secondary is 25 grounded. When the contact 14a is engaged by the contact-maker 14 during the passage of an unstemmed leaf under the detector roll 6, the circuit through the electro-magnet is closed and the circuit breaker 83 is thus closed, whereupon 30 the core 77 of solenoid 76 forces the shoe 80 against the pin or pins 73 then registering with it, and pushes the same back through the web of gear 71 into position to block the movement of the arm 74, thereby maintaining the rollers 54 35 35 in their lower position at the time when the leaf which has caused contact 14 to close reaches the delivery end of the transfer belt 27. As the gear 71 continues its rotation, the displaced pin or pins 73 engage a stationary cam-piece 88 attached to frame 75 and are reset forwardly in a position to clear the arm 74 before they again come into registration with the pusher 80.

When the pins 73 remain in their normal or neutral position, as during the passage under 45 detector roller 6 of properly stemmed leaves, the rollers 54 are raised by cam 68 into position 54' wherefore the belt 55 is normally maintained in its raised position when a properly stemmed leaf is discharged from belts 27 and the separate halves 50 L' of the leaf are then deposited upon the perforated conveyor belts 53 which by rollers 89, 90 and 91 are guided over a suction chamber 92 and around a large drum 93 on a shaft 94 and under the suction chamber. Endless belts 95, guided 55 and kept taut by rollers 96, 97, 98, 99 and 91 along the top of suction chamber 92 and around the drum 93, press the separate halves L' of the leaf against conveyor belts 53 during their passage over chamber 92 and around drum 93, there- 60 by compressing and straightening the leaf.

The shaft 100 of rollers 89 is driven from shaft 31 by a sprocket chain 101. The shaft 94 of drum 93, by a sprocket chain 102, drives the shaft 58 of rollers 57, and shaft 58 carries a 65 gear 103 driving a gear 104 on the shaft 105 of rollers 91. The outspread halves L' of the leaf are retained on the belt 53 while being carried under the chamber 92, by the suction in the chamber applied through the perforations of the 70 belts 53, into position over screens 106 conveyed transversely of the belts 53 on chains 107 driven by sprockets 108 on a shaft 109 supported by bearings 110 on the frame 111. When the leaf halves arrive at the proper position for delivery 75

- to one of the screens 106, as seen in Fig. 3, the suction in chamber 92 is cut off by a valve 112 in suction pipe 113, this valve being connected by a rod 114 to a cam lever 128 actuated from a cam 5 (not shown) on shaft 10. At the same time a rod 115 actuated by a cam lever 116 controlled by a cam 117 on shaft 10 turns a bell-crank 118 on chamber 92, thereby, through bar 119 and levers 120 and 121 depressing a plate 122 within 10 chamber 92, thus expelling air from the same. Fingers 123 attached to plate 122 carry bars 124, Fig. 3, which normally lie in recesses in the under side of the bottom of chamber 92 so that they do not interfere with the leaves carried by 15 the belts 53. When the plate 122 is depressed, the bars 124 push the leaf L' off the belts 53 and aided by the blast of ejected air, deposit it on the screen 106, thereby insuring its proper delivery to the latter.
- 20 While it is desirable to split the stemmed leaves in case they are to be blended, it will be understood that this splitting operation may be omitted. Furthermore, while it is desirable before blending, to collect the separate leaf halves 25 on screens so that they may be readily introduced into the drier, the leaves, split or unsplit, may be collected on an endless traveling surface such as a delivery belt or the like. The leaves are preferably deposited in overlapping relation 30 on the screens, the latter being suitably timed for that purpose with relation to the mechanism for stemming the tobacco leaves and depositing them on the screens.
- What is claimed is:
- 35 1. In a stemming machine, the combination with mechanism for stemming tobacco leaves, of mechanism for advancing the stemmed leaves, a device for detecting unstemmed and insufficiently stemmed leaves among the leaves advanced 40 by said leaf-advancing mechanism, and means controlled by said device for diverting the unstemmed and insufficiently stemmed leaves from said leaf-advancing mechanism, said leaf-advancing mechanism including an endless traveling 45 conveyor belt arranged to receive and deliver the stemmed leaves at a predetermined point, and endless traveling members acting to transport the stemmed leaves under said device to said conveyor belt, and said means including an 50 endless traveling delivery belt, a guide roller adjacent the point at which the stemmed leaves are delivered from said members to said belt, the delivery belt being looped over said guide roller, and means connected to said device for lowering 55 said roller to bring the delivery belt into position to receive a faulty leaf detected by said device.
2. The combination with mechanism for advancing stemmed leaves, of members coacting with said mechanism for compressing the advancing leaves, so that they will be delivered by 60 said mechanism in flat condition, said mechanism including a traveling endless conveyor belt, and said members including a drum over which said conveyor belt is looped, around substantially a 65 semi-circumference of the drum a compressor belt looped over said drum outside, and co-extensive in area with the aforesaid area of said conveyor belt, and rollers arranged to guide and keep said belts taut whereby a stemmed leaf 70 delivered between the same will be compressed and delivered in flat condition, a device for advancing screens horizontally under said mechanism at the proper speed and in a direction such that the stemmed leaves will be delivered on the 75 screens in sidewise overlapping relation, and

means for stemming tobacco leaves and delivering them in outspread condition to said mechanism.

3. In a stemming machine, the combination with means for forwarding stemmed leaves, of a device for detecting unstemmed leaves among the advancing leaves, mechanism independent of said device for receiving the leaves directly from said leaf-forwarding means and delivering them in a predetermined position, and instrumentalities controlled by said device for engaging and carrying and thereby removing the unstemmed leaves positively from the normal path in which the stemmed leaves are advanced by said mechanism, before they reach said predetermined 15 position.

4. In a stemming machine, the combination with means for stemming tobacco leaves while forwarding them tip foremost, of mechanism engaging the tips only of the stemmed leaves advanced by said means to thereby crush the remaining portions of the stems of properly stemmed leaves and the tip portions only of the stems of improperly stemmed and unstemmed leaves, and members for slitting lengthwise the 25 crushed stem portions of successive leaves advanced by said means to thereby separate the properly stemmed portions only into halves.

5. The combination with mechanism for advancing stemmed and split leaves, of members 30 coacting with said mechanism for compressing the advancing leaves, so that they will be delivered in that condition, said mechanism including traveling endless conveyor belts, and said members including a drum over which said conveyor belts are looped, and compressor belts looped over said drum outside said conveyor belts and coacting therewith to compress the stemmed leaves thereagainst and arranged to guide the leaves on said conveyor belts over said drum and 40 deliver them individually and horizontally below said drum and means for advancing screens horizontally below said drum at the proper speed and in a direction to permit the leaves to be delivered on the screens in sidewise overlapping 45 relation.

6. In a stemming machine, the combination with mechanism for advancing leaves to a predetermined point, of means for stemming tobacco leaves and delivering them directly to said mechanism, a device for detecting unstemmed and insufficiently stemmed leaves among the leaves advanced by said means, and positive means controlled by said device for engaging and carrying and thereby switching the unstemmed and insufficiently stemmed leaves from the normal path in which the stemmed leaves are advanced directly to said point by said mechanism before they reach said mechanism, leaving the stemmed leaves under the influence and control of said 60 mechanism for such direct advancement to said predetermined point.

7. In a stemming machine, the combination with mechanism for advancing leaves to a predetermined point, of means for stemming tobacco 65 leaves and delivering them to said mechanism, a device for detecting unstemmed leaves among the leaves advanced by said mechanism, an endless belt, and means controlled by said device for moving said belt bodily into a position wherein 70 the unstemmed and insufficiently stemmed leaves will be deposited on said belt and thus diverted before they reach said predetermined point.

8. The combination with mechanism for advancing stemmed tobacco leaves comprising a 75

plurality of opposed belts between which the leaves are gripped, of a drum about which said belts are looped for compressing the advancing leaves as they pass around said drum, said belts having at least one straight conveying belt run at the entrance and exit sides of the looped portions for conveying said leaves into and out of operative relation to said drum and the portions of said belts coacting with said drum, at least one of said belts being provided with suction openings, a suction chamber on the one side of said belt on the delivery run thereof and means for periodically cutting off the suction to permit delivery of the flattened leaf from said belt.

9. In a stemming machine, the combination with mechanism for advancing leaves to a predetermined point, of means for stemming tobacco leaves and delivering them to said mechanism, a device detecting improperly stemmed leaves among the leaves advanced by said mechanism, an auxiliary conveyor and means controlled by said device for moving said auxiliary conveyor into position to intercept and divert improperly stemmed leaves from the properly stemmed ones before they reach said predetermined point.

10. In a stemming machine, the combination with a suction chamber having a perforated bottom, of a series of perforated endless traveling belts disposed in spaced relation and having runs overlying said chamber, and other runs underlying said perforated bottom, mechanism for stemming and splitting tobacco leaves and delivering the separated leaf-halves on said overlying runs, traveling members acting to retain the leaf-halves on said belts while they are advanced on to said perforated bottom, whereby the leaf-halves will be suctionally retained on said belts, and means for periodically cutting off the suction from said chamber to cause the leaf-halves to be delivered therebelow at a desired point.

11. In a stemming machine, the combination with mechanism for stemming tobacco leaves, of means arranged to receive the leaves and advance them in a path leading to a delivery station, a device for advancing the leaves from said mechanism directly to said means and detecting unstemmed and insufficiently stemmed leaves among said leaves, and a member controlled by said device for movement into a position wherein it positively engages and carries and directs unstemmed and insufficiently stemmed leaves away from said means and thereby effects segregation as between the same and the properly stemmed leaves by diverting the unstemmed and insufficiently stemmed leaves from said path before they reach said means.

12. In a stemming machine, the combination with mechanism for removing the major portion of the stem of a tobacco leaf, of a device for advancing the stemmed leaf tip foremost and crushing the remaining portion of the stem, said device including a crushing roll and mechanism for intermittently moving said roll into engagement with the unstemmed tip portions only of successive leaves advanced by said device and thereby crushing the stem portions therein.

13. In a stemming machine, the combination with mechanism removing the major portion of the stem of a tobacco leaf and leaving the tip end thereof unstemmed, of members for advancing the stemmed leaf with its unstemmed tip foremost to a predetermined point, and means for splitting the unstemmed portion of the advancing leaf to separate the halves of the same, said means including a rotary knife, and members for periodically moving said knife to and from a position wherein it will engage and sever the unstemmed portion only of said leaf.

RUPERT E. RUNDELL. 40
